UNITED STATES PATENT OFFICE.

EDGAR F. HATHAWAY, OF DORCHESTER, MASSACHUSETTS, ASSIGNOR TO MOHAWK CARPET MILLS, INC., OF AMSTERDAM, NEW YORK, A CORPORATION OF NEW YORK.

CHENILLE-STRIP DISTRIBUTION.

1,392,939.

Specification of Letters Patent. Patented Oct. 11, 1921.

Application filed March 8, 1921. Serial No. 450,613.

To all whom it may concern:

Be it known that I, EDGAR F. HATHAWAY, a citizen of the United States, and a resident of Dorchester, in the county of Suffolk and State of Massachusetts, have invented an Improvement in Chenille-Strip Distribution, of which the following description, in connection with the accompanying drawings, is a specification, like 10 characters on the drawings representing like parts.

This invention relates to chenille strip distribution both as mechanism and as process or method.

15 In order that the principle of the invention may be readily understood, I have in the accompanying drawings disclosed a single embodiment of the mechanism of my invention and the best mode known to me 20 for carrying out my method.

In said drawings,—

Figure 1 is a plan view largely diagrammatic of chenille strip forming mechanism and indicating the distribution thereof in 25 accordance with my invention;

Fig. 2 is a side elevation of the structure shown in Fig. 1;

30 Fig. 3 is a side elevation of a part of the structure shown in Figs. 1 and 2, but on a larger scale and indicating the driving means for certain of the parts;

Fig. 4 is a vertical transverse section on the line 4—4 of Fig. 3 and looking toward the left in said figure; and

35 Fig. 5 is a vertical sectional view upon the line 5—5 of Fig. 4 and looking toward the right in said figure.

I have indicated generally at 1 in Figs. 1 and 2 mechanism for forming chenille strips. This mechanism is fully disclosed 40 in my co-pending applications Serial Nos. 449,887 and 449,888, both filed March 5, 1921, and need not be here specifically described. It is sufficient for the purpose of this invention to state that longitudinally extending straight warp threads 2 supported upon beams 3 and so-called doup warp threads 4 supported upon beams 5 are shedded as indicated at 6 and a suitable weft or filling is 45 there incorporated preferably by means of a weft carrier as indicated in my said applications and the woven material 7 is passed between cutter members 8 whereby as disclosed in my co-pending application Serial No. 50 449,887 the woven material is severed into

chenille strips between the warp threads, such strips being moistened as indicated at 9 and then heated or dried as indicated at 10 into chenille strips. Such chenille strips pass about a shaft 11 driven by gearing in 60 any suitable manner from the main drive shaft of the mechanism and then are conducted in accordance with my invention for distribution and accumulation.

In order effectively to distribute and accumulate the chenille strips which it will be understood are customarily woven in colors according to the dictates of a pattern, so that each of said strips may be parti-colored throughout its length, I prefer- 65 erably provide the following mechanism.

A suitable number of uprights 12 support an overhead rectangular framing 13, 14 wherein are received a suitable number of driven rolls 15 over which the chenille 75 strips pass and downward from which the strips descend into the cans or receptacles 16.

The operative stands upon a platform 17 under which the chenille strips 18 pass, the 80 operative customarily facing the chenille forming mechanism 1 so that the upright framing and the cans are at his back. The cans 16 may be if desired supported upon stands 19 or upon the floor and are arranged 85 desirably in series under the rolls 15 substantially as indicated in part in Fig. 1. In said figure, I have indicated at *a* a set of three guiding and delivery rolls 15, at *b* a similar set of three rolls, at *c* a similar set 90 and at *d* still another similar set, and beneath each set of said rolls I have in the disclosed embodiment of the invention positioned eighteen cans or receptacles 16. I have indicated the distribution of twelve 95 chenille strips to each set of twelve cans 16, three of such cans of each set pertaining to each of the groups *a*, *b*, *c* and *d*. As shown clearly in Fig. 1, the twelve strips in each of the six sets pass side by side and in close 100 relation over the first of said rolls 15 as indicated in Fig. 1. One of the chenille strips of each of said six sets as indicated in Fig. 1 passes downwardly from said first roll 15 into the receptacle underneath. The 105 remaining eleven strips of each of said six sets pass to the second roll and the next strip thereof passes down into the can 16 beneath such roll. The remaining ten strips of each of said sets pass on and in the man- 110

ner already described said strips descend one by one into the respective cans beneath the respective rolls until the last strip of each set passes down into the can of its 5 series directly beneath the last roll 15 of the group *d*. Thus I take care of twelve chenille strips by a single line of cans 16. Since the cans 16 are arranged in six longitudinally extending rows, it is evident 10 that by the construction indicated I take care of seventy-two chenille strips.

It will be understood that viewing Fig. 1 the first chenille strip counting from the left-hand side of the chenille forming mechanism, is deposited in the first can of the first 15 series, namely, the can at the extreme corner of the framing at the end nearest the operative, and that the last chenille strip counting 20 from the same side, that is, of the same set, is deposited in the last can at the same side but opposite end of the framing.

Thus it will be understood that the chenille strips are regularly and methodically 25 deposited and in such manner that access may readily be had to the desired color or character of strips, if they differ among themselves. The chenille cans 16 may be of any suitable character and are not herein 30 claimed. As disclosed in my co-pending application Serial No. 449,886, filed March 5, 1921, they are, however, preferably of a cylindrical construction and have a detachable cover for each end, so that the material may 35 be received through the open upper end of the can when in the position shown, the said can having its bottom cover detachably secured in place. After the can has been filled, the top cover is secured in place, the can is 40 inverted, the lower cover is removed, and then the chenille strip is drawn out in the direction in which it was deposited.

In order to drive the rolls 15 and the co-operating parts, any suitable means may be 45 provided. For this purpose, I have represented the shaft 11 as having thereon a sprocket gear 20 about which passes a sprocket chain 21, the two runs of which 50 pass respectively about sprocket gears 22, 23, supported by suitable brackets 24, 25 at the lower part of one of the uprights 12. The 55 said sprocket chain passes about a sprocket gear 26 shown most clearly in Fig. 4, which is loose upon a shaft 27 supported in the longitudinally extending members 14 of the framing. The said shaft has loose thereon a roll 14' positioned in advance of the series 60 of rolls 15 and between which may be loosely supported the roll 14''. Said roll 14' is shown as formed as a shell or cylinder provided with sprocket gears 28, 29 into circular recesses in the faces of which the circular shell 14' is received. The said parts are secured together by tie rods 30 passing through 65 the gears 28, 29 and having at one end bolts

31. Said tie rods extend through the gear 28 and through a ratchet wheel 32, at the outer face whereof they receive nuts 33 rigidly securing the parts together. The ratchet wheel 32 is mounted upon the hub of the 70 sprocket gear 28 and rotates therewith as a part of the roll structure 14'. The said roll structure 14' is as stated loose upon the shaft 27.

Keyed to the sprocket gear 26 is a radially 75 extending arm 34 carrying a pawl 35 shown in side elevation in Figs. 3 and 5. The said pawl engages the teeth of the ratchet wheel 32. The construction and mode of operation are such that the sprocket chain 21 passing 80 over the sprocket gear 26 rotates the same in a clockwise direction viewing Fig. 5 and hence through corresponding movement of the pawl 34, which is in constant relation with the teeth of the ratchet 32, drives the 85 latter and consequently the roll 14' in a clockwise direction.

A sprocket chain 36 passes about the sprocket gear 29 at the opposite end of the roll 14' and about a corresponding sprocket 90 gear fast on the shaft of the first roll 15 and accordingly drives such roll in the same direction. Said first roll 15 is provided with a similar sprocket gear at its other end whereon is received a sprocket chain 37 passing 95 about a sprocket gear on the corresponding end of the second roll 15 to drive the latter, and this arrangement is continued throughout the entire series of rolls 15.

I have indicated diagrammatically at 100 Fig. 2 manual means whereby the chenille forming mechanism may be turned backward at any time and for any purpose, as for example when a weaving defect occurs. It is 105 obvious that the turning backward of the chenille forming mechanism results in the turning backward of the chenille strips 18 and unless means be provided to prevent the same, the chenille strips or parts thereof would be withdrawn from the cans 16. It is 110 to prevent such withdrawal from the cans 16 that I have provided the pawl 35 and ratchet 32. It is obvious that when by the manual means 38 the shaft 11 is turned backward and the sprocket chain 21 is turned back- 115 ward, the pawl 35 is drawn in a counter-clockwise direction idly backward over the teeth of the ratchet 32 and imparts no movement thereto. Thus all the rolls 15 remain stationary during the backward movement 120 of the other part of the mechanism.

It will thus be evident from the foregoing description that I have provided a convenient and compact organization of parts 125 whereby a very large number of chenille strips are or may be accumulated in their respective cans or receptacles in regular order and in such manner as readily to permit access to any can or receptacle 16 and so that the mechanism may be turned back- 130

ward without disturbing the accumulated material in the cans.

While I have described my invention both as to mechanism and method with particular reference to chenille forming mechanism, I desire it to be understood that in certain aspects of my invention it is capable of use in other relations and for other purposes.

Having thus described one illustrative embodiment of my invention I desire it to be understood that although specific terms are employed they are used in a generic and descriptive sense and not for purposes of limitation, the scope of the invention being set forth in the following claims.

Claims:

1. Chenille or like strip distributing mechanism comprising in combination, mechanism extending the full width of the chenille forming mechanism to deliver in parallel relation from the said chenille forming mechanism a set of laterally uncontracted strips and constituting substantially a sheet which is of the full width of the mechanism, a series of receiving receptacles in substantial alinement, and means to direct said strips separately into the respective receptacles, whereby each receptacle receives a single strip.
2. Chenille or like strip distributing mechanism comprising in combination, means extending the full width of the chenille forming mechanism to deliver in parallel relation from the said chenille forming mechanism a plurality of sets of laterally uncontracted strips and constituting substantially a sheet which is of the full width of the mechanism, a corresponding plurality of sets of receiving receptacles, the receptacles of each set being in substantial alinement, and the several sets being in parallelism, and means to direct the strips of each set separately into the respective receptacles of that set, whereby each receptacle receives a single strip.
3. Chenille or like strip distributing mechanism comprising in combination, means extending the full width of the chenille forming mechanism to deliver in parallel relation from the said chenille forming mechanism a plurality of sets of laterally uncontracted strips and constituting substantially a sheet which is of the full width of the mechanism, a plurality of sets of receiving receptacles, the receptacles of each set being in substantial alinement, and means to direct the strips of each set into the respective receptacles of that set whereby each receptacle receives a single strip.
4. Chenille or like strip distributing mechanism comprising in combination, means extending the full width of the chenille forming mechanism to deliver in parallel relation from the said chenille forming mechanism a series of laterally uncontracted

strips and constituting substantially a sheet which is of the full width of the mechanism, a substantially rectangular framing, receptacles positioned within said framing, and means carried by said framing to direct the respective strips downwardly into the receptacles, so that a single strip is delivered to each receptacle.

5. Chenille or like strip distributing mechanism comprising in combination, means extending the full width of the chenille forming mechanism to deliver in parallel relation from the said chenille forming mechanism a series of sets of laterally uncontracted strips and constituting substantially a sheet which is of the full width of the mechanism, a substantially rectangular framing, a series of sets of receiving receptacles positioned within the framing, delivery rolls carried by the framing above the receptacles and positioned to direct the strips respectively downwardly into the several receptacles, and means to drive all of said rolls in unison in a forward direction.

6. Chenille or like strip distributing mechanism comprising in combination, means extending the full width of the chenille forming mechanism to deliver in parallel relation from the said chenille forming mechanism a series of sets of laterally uncontracted strips and constituting substantially a sheet which is of the full width of the mechanism, a substantially rectangular framing, receptacles supported within the same, delivery rolls carried by the framing above the receptacles and adapted to receive the strips from the forming mechanism and to deliver them directly downward into the respective receptacles, and means to rotate all of said rolls in a forward direction.

7. Chenille or like strip distributing mechanism comprising in combination, means extending the full width of the chenille forming mechanism to deliver in parallel relation from the said chenille forming mechanism a series of sets of laterally uncontracted strips and constituting substantially a sheet which is of the full width of the mechanism, a substantially rectangular framing, receptacles supported within the same, delivery rolls carried by the framing above the receptacles and adapted to receive the strips from the forming mechanism and to deliver them directly downward into the respective receptacles, means to rotate all of said rolls in a forward direction, and means whereby chenille forming mechanism may be driven backwardly without withdrawing the strips from the receptacles.

8. Chenille or like strip distributing mechanism comprising in combination, means extending the full width of the chenille forming mechanism to deliver in parallel relation from the said chenille forming mechanism a plurality of sets of laterally uncontracted

tracted strips and constituting substantially a sheet which is of the full width of the mechanism, a substantially rectangular framing, a plurality of sets of receptacles 5 therein and corresponding in number to the number of chenille strips, said receptacles being arranged in a plurality of parallel sets, the receptacles of each set being at successively greater distances from the chenille 10 forming mechanism, and means carried by the framing to direct each strip into its own receptacle.

9. Chenille or like strip distributing mechanism comprising in combination, means extending the full width of the chenille forming mechanism to deliver in parallel relation from the said chenille forming mechanism a plurality of sets of laterally uncontracted strips and constituting substantially 15 a sheet which is of the full width of the mechanism, a framing, a plurality of sets of receptacles beneath the framing and corresponding in number to the number of strips, said receptacles being arranged in 20 parallel series, delivery rolls carried by the framing above the receptacles, each roll being positioned to deliver one strip of each set into the receptacle corresponding thereto.

10. Chenille or like strip distributing mechanism comprising in combination, means extending the full width of the chenille forming mechanism to deliver in parallel relation from the said chenille forming mechanism a plurality of sets of laterally uncontracted strips and constituting substantially a sheet 35 which is of the full width of the mechanism, a framing, a plurality of sets of receptacles beneath the framing and corresponding in number to the number of strips, said receptacles being arranged in parallel sets, delivery rolls carried by the framing above the receptacles, each roll being positioned to deliver one strip of each set into the receptacle corresponding thereto, and means to drive 40 all of said rolls in unison.

11. Chenille or like strip distributing mechanism comprising in combination, means to deliver in parallel relation from the chenille forming mechanism a set of strips, a framing, receptacles supported within the same, delivery rolls carried by the framing above the receptacles and adapted to receive the strips from the forming mechanism and to deliver them directly downward into the 50 respective receptacles, means to rotate all of said rolls in a forward direction only, and means whereby the chenille forming mechanism may be driven backwardly without withdrawing the strips from the receptacles.

60 12. Chenille or like strip distributing mechanism comprising in combination, means extending the width of the chenille forming mechanism to deliver in parallel relation from said chenille forming mechanism a set of strips which is of the full width of said

mechanism, a substantially rectangular framing, receptacles supported within the same, delivery rolls carried by the framing above the receptacles and adapted to receive the strips from the forming mechanism and to deliver them downward into the respective receptacles, means to rotate all of said rolls in a forward direction, and means whereby chenille from the mechanism may be driven backwardly without withdrawing 75 the strips from the receptacles.

13. Chenille or like strip distributing mechanism comprising in combination, means to deliver in parallel relation from the chenille forming mechanism a set of strips, a substantially rectangular frame, receptacles supported within the same, delivery rolls carried by the frame above the receptacles and adapted to receive the strips from the forming mechanism and to deliver them directly downward into the respective receptacles, means to rotate all of said rolls in a forward direction only, and means whereby chenille forming mechanism may be driven backwardly without withdrawing 80 the strips from the receptacles, said latter means including a ratchet and pawl drive 85 for all of said delivery rolls.

14. Chenille forming and chenille strip distributing mechanism comprising in combination, mechanism to form chenille and to reduce the same to strips, mechanism to deliver in parallel relation a set of strips from the said chenille forming mechanism and a series of receptacles sufficiently spaced 95 from the chenille forming mechanism to permit the operative to stand between said chenille forming mechanism and said series of receptacles, said receptacles being in substantial alinement, and means to direct the several strips separately into the respective receptacles, whereby each receptacle receives 100 a single strip.

15. Chenille forming and chenille strip distributing mechanism comprising mechanism to form chenille and to reduce the same to strips, mechanism extending the entire width of the chenille forming mechanism to deliver in parallel relation from the said chenille forming mechanism a set of strips which is of the full width of said mechanism, and a series of receiving receptacles for said strips, said series of receptacles being as an entirety sufficiently spaced from and so related to the chenille forming mechanism as to permit an operative to stand between said chenille forming mechanism and said series of receptacles, the latter being in substantial alinement, and means to direct 115 said strips separately into the respective receptacles, whereby each receptacle receives a single strip.

16. Chenille forming and chenille strip distributing mechanism comprising in combination, mechanism to form chenille and to 120

reduce the same to strips, mechanism to deliver a set of strips from said chenille forming mechanism and a series of receptacles sufficiently spaced as an entirety from the 5 chenille forming mechanism to permit the operative to position himself between said chenille forming mechanism and said series of receptacles, and means to direct the several strips separately into the respective receptacles, whereby each receptacle receives 10 a single strip.

17. Chenille forming and chenille strip distributing mechanism comprising in combination mechanism to form chenille and to 15 reduce the same to strips, mechanism to de-

liver in substantially parallel relation a set of strips from said chenille forming mechanism, a platform 17 under which the set of strips passes and upon which the operative may position himself, and a series of receptacles spaced as an entirety from said chenille forming mechanism by said platform 17, and means to direct the several strips separately into the respective receptacles, whereby each receptacle receives a 20 single strip.

In testimony whereof, I have signed my name to this specification.

EDGAR F. HATHAWAY.
